American Type Founders, Inc., Elizabeth,
N. J., a corporation of New Jersey

Application November 30, 1939, Serial No. 88,584

Term of patent 7 years

To all whom it may concern:

Be it known that I, Frank H. Riley, a citizen of the United States, residing at New York, county and State of New York, have invented a new, original, and ornamental Design for a Font of Type, of which the following is a specification, reference being had to the accompanying drawing, forming part thereof.

The drawing is a face view of a font of type showing my design.

I claim as my invention:

The ornamental design for a font of type, as shown.

FRANK H. RILEY.
